UNITED STATES PATENT OFFICE.

AUBREY EDWIN JEUNE, OF TORONTO, ONTARIO, CANADA.

ELECTRIC-FIXTURE CANOPY.

1,270,296.

Specification of Letters Patent. Patented June 25, 1918.

Application filed December 8, 1916, Serial No. 135,819. Renewed November 19, 1917. Serial No. 202,870.

To all whom it may concern:

Be it known that I, AUBREY EDWIN JEUNE, of the city of Toronto, in the county of York, in the Province of Ontario, Canada, 5 have invented certain new and useful Improvements in Electric-Fixture Canopies, of which the following is the specification.

My invention relates to improvements in electric fixture canopies and the object of the 10 invention is to devise a simple form of canopy which may be quickly and readily removed for inspection purposes and from which the full weight of the fixture may depend thus dispensing with any insulated gas 15 pipe connection commonly employed and it consists essentially of the following arrangement and construction of parts as herein-after more particularly explained by the following specification.

20 Figure 1, is a general perspective view of my canopy attached to a ceiling.

Fig. 2, is a sectional view through Fig. 1.

Figs. 3, 4 and 5 are perspective details of the parts comprising the canopy separated 25 apart.

Fig. 6, is a sectional view of an alternative construction.

Fig. 7, is a perspective detail of the base plate shown in Fig. 6 and the depending 30 hanger secured thereto.

In the drawings like letters of reference indicate corresponding parts in each figure.

1 indicates an annular plate provided with diametrically disposed depending are-shape 35 flanges 2 and 3 and recesses 4 and 5 interposed between the opposite ends of the opposing flanges 2 and 3. The annular plate 1 is secured to the ceiling by a plurality of screws 6 extending through screw orifices 7

40 formed in the plate preferably arranged circularly in proximity to the outer edge of the plate.

8 indicates the main portion of the canopy, the upper annular flange 8' of which is provided with diametrically opposing inturned flange extensions 8² and 8³.

When connecting the main portion of the canopy 8 in position all that it is necessary to do is to place the flange 8' of the canopy 45 around the plate 1 to the outside of the depending flanges 2 and 3 so that the flange extensions 8² and 8³ pass through the recesses 4 and 5 against the face of the ceiling indicated by the numeral 9. The member 8 is 55 then given a quarter turn whereby the flange extensions 8² and 8³ are carried circumferen-

tially into position between that portion of the plate 1 carrying the depending flanges 2 and 3 between the face of the ceiling or into the position shown in Fig. 2, the flanges 2 and 3 in this position bearing against the inner face of the annular flange 8'. The canopy member 8 may carry depending hooks 10 from which depend chains usually employed for supporting a chandelier or other lighting fixture. The canopy may also be divided into two portions, the main portion as above described terminating at its lower end in an annular depending flange 11 and the member 12 substantially dome-shape in form and provided with an upwardly extending annular flange 13 designed to fit around the flange 11. The flange 13 is provided with a perforation 14 into which a pin or other suitable projection 15 extending 75 from the flange 11 is sprung when forcing the flange 13 over the flange 11. The flanges 13 and 11 are also provided with aligned orifices 16 and 17 located diametrically opposite the perforation 14 and projection 15. 80 17* indicates a securing screw which is screwed into the aligned orifices 16 and 17. The lower end of the canopy member 12 is provided with a center opening 18 through which electric cords are designed to pass. 85 The orifice 18 may also be provided with an internally threaded nipple 19 having an outer flange 20 bearing against the outer face of the dome and an inner flange 21. 22 indicates a reinforcement of comparatively 90 thick metal which is inserted in the dome and around the nipple and over the inner edge of which the flange 21 extends. 23 indicates a depending fixture pipe which is 95 threaded into the nipple 19.

When the canopy is used for a horizontal bracket it will be readily seen that the reinforcement 22 serves to reinforce the edges of the orifice 18 and prevent the buckling of the metal due to the weight of the 100 fixture on the horizontal fixture pipe 23 tending to buckle the metal at this point and sag it downwardly.

In the event of the hooks 10 being used to support the electric fixture all that it is necessary to do when inspecting the interior of the canopy is to remove the screws 17 and the lower portion 12 of the canopy from the upper portion, the upper portion still being secured to the ceiling and carrying the 110 weight of the chandelier.

If it is desired to move the whole canopy,

of course, all that it is necessary to do is to give the canopy member 8 a quarter turn so as to move the flange extensions 8² and 8³ opposite the recesses 3 and 4 when the whole 5 canopy and fixtures carried thereby may be lowered.

In Figs. 6 and 7, I have shown an alternative construction in which 24 indicates the base plate which is of the same construction as the base plate 4 shown in Figs. 1, 2 and 3 with the exception that it is provided with a pair of depending lugs 25 and 26. 27 indicates a substantially U-shaped hanger member riveted or otherwise suitably secured to the lugs 25 and 26. The U-shaped member 27 comprises the side arms 28 and 29 having inturned portions 30 and 31 connected by an internally threaded nut-shaped portion 32. 33 indicates a tubular member secured in the portion 32 and provided with an externally threaded lower end. 34 indicates a canopy which covers the hanger member 29 and is secured to the base plate 24 in a similar manner to that described in connection with Figs. 1, 2 and 3. The lower end of the canopy is provided with an orifice 35. 36 indicates a cap provided with an internally threaded boss 37 screwed on to the lower externally threaded portion of the 30 tubular member 33. The cap 36 is provided with an external shoulder 38 between which and the nut-portion 34 extends an outer,

tube 39 which fits the orifice 35 of the canopy. The cap portion 36 is provided with an eye 40 from which a chandelier or other 35 depending structure may be hung. By this construction it will be seen that the entire weight is carried by the base plate 24 taking all strain off the canopy.

From this description it will be seen that 40 I have devised a very simple form of canopy for electric fixtures which may serve to carry the whole weight of the fixture proper and thus dispense with all insulating joints and at the same time provides a simple 45 ready and easy means for removing the canopy or portion thereof so as to enable an inspector to inspect the electric connections covered by the same.

What I claim as my invention is. 50

In an electric canopy, a circular base member having recesses in the diametrically opposite peripheral portions, of a canopy member adapted to encircle and inclose the base member having horizontally inwardly 55 extending opposing flange portions adapted to pass through such recesses when the canopy is placed in position and to be carried between the base member and ceiling by circumferential movement.

AUBREY EDWIN JEUNE.
